INVENTOR
William W. Patton,
By Joshua Pusey, *Pat.*

UNITED STATES PATENT OFFICE.

WILLIAM W. PATTON, OF PHILADELPHIA, PENNSYLVANIA.

COMBINED OPEN GRATE AND HEATER.

SPECIFICATION forming part of Letters Patent No. 317,006, dated May 5, 1885.

Application filed February 1, 1884. (No model.)

To all whom it may concern:

Be it known that I, WILLIAM W. PATTON, a citizen of the United States, residing at the city and county of Philadelphia, and State of Pennsylvania, have invented certain new and useful Improvements in a Combined Open Grate and Heater, of which the following is a full, clear, and exact description, reference being had to the accompanying drawings.

10 The nature of this invention is a combined open grate and heater adapted to be applied in connection with the ordinary fire or chimney places, and its object is to utilize a portion of the heat (which in ordinary open grates usually escapes up the chimney) for heating air or water for warming an upper room. I accomplish this result by combining with an open grate an arrangement of hot-air flues or chambers, such as I shall now proceed to describe, 15 reference being had to the annexed drawings, of which—

Figure 1 is a front elevation of my invention in position in a chimney-place; Fig. 2, a top view of the same when detached; Fig. 3, a 20 vertical sectional view thereof, as on the line *a a*, Fig. 1, looking in the direction of the adjacent arrow on the right; Fig. 4, a similar sectional view as on line *b b*, looking in the direction of the arrow on the left; Fig. 5, a 25 horizontal sectional view on line *c c*; Fig. 6, a middle vertical section on line *d d*, and Fig. 7 a like section of the invention as adapted for heating water instead of air.

Like letters of reference where they occur 30 in the several figures indicate the same or corresponding parts.

A is the open grate, contained in an alcove in the front of the air-box B, which box is formed so as to fit or may be readily fitted into 35 an ordinary fire or chimney place. The rear wall or partition of said alcove has extending across the same an angular projecting partition, C, extending over and above the back part of the coal-space of the grate, the function of which is to deflect the flame outwardly, and also to present an increased and efficient 40 heating-surface for the air that, as will be explained further on, circulates immediately back of and in contact with said partition, and 45 which constitutes a large portion of the front

of the main air-chamber D, separated from flue G by partition *k*.

The smoke and other products of combustion from the coals E pass up the chimney J, Fig. 1, of the building by way of the short 50 flue F connecting therewith.

At one side of the box B—the left side in the present instance—is a vertical chamber, G, whose side *h* forms one of the lateral walls of the aforesaid alcove. On the other or right side is a large chamber or air-space, D, extending also back of the rear partition of the alcove. This chamber extends around and is separated from the flue G by a partition, *k*, communicating by an opening, *l*, with the flue 55 N, Fig. 1, leading up to the apartment to be heated. It is preferred to carry this hot-air flue N up the chimney, in order to secure the advantage of the heat escaping up the latter. The chambers D and G communicate by means 60 of the horizontal air-conduit I, whose bottom wall is the top partition of said alcove, and whose rear wall is the front of the short smoke-flue F. By the described construction it will be perceived that a large heating-surface for 65 the air within the said chamber is obtained.

The cold air enters the spaces D and G through registers R at the base, opening into the room; or, by a suitable connection, the air may be taken from out of doors, if preferred. 70 The body of air entering chamber G comes into contact with the partition *h*, by which it is heated to some extent, then ascends and passes on through the conduit I, by whose bottom and rear walls it is further heated, and mingles 75 with the air in chamber D, which has entered the latter through the register at its base. The latter body of air is heated by the side wall of the alcove, and the combined currents circulate around back of the latter and the flue 80 F, coming into contact also with the highly-heated walls of the angular projection C, thence ascending the flue leading to the apartment to be heated through the opening *l*. A low partition, *m*, Fig. 5, and indicated by the broken 85 lines in Fig. 1, extending vertically across chamber D, serves to direct the cold air upward as it enters the registers toward the heating-surface.

In order to adapt the invention for heating 90

water in lieu of air for a like purpose, I simply seal up the registers R and the opening l and connect with the chambers, or one of them, a circulating water pipe system—such as, for example, that illustrated in Fig. 7, in which P P marks the system of water-pipes, communicating with the top and bottom, respectively, of chamber D and extending with as many turns as desired into the room to be heated.

Having thus described my invention, I claim as new and desire to secure by Letters Patent—

1. The combination, with an open grate, of the air-chambers G D, provided with bottom openings for the admission of air, of the horizontal box-chamber I, connecting said chambers G D, the grate-flue F, interposed between the chambers G I D, and the side outlet-opening l, substantially as described, and for the purposes set forth.

2. The combination of the open grate, the vertical side air-flue, G, the side and rear flue or chamber, D, said flues communicating by means of the horizontal flue I, and provided with the openings or registers R, all constructed, arranged, and adapted to operate substantially as described. 25

3. In combination with an open grate, the chambers G and D, separated on one side by partition k, and connected by the horizontal chamber I, the chamber D being provided with a low partition, m, substantially as described, and for the purposes set forth. 30

In testimony whereof I have hereunto affixed my signature this 22d day of January, A. D. 35 1884.

WILLIAM W. PATTON.
